UNITED STATES PATENT OFFICE.

FELIX O'DONNELL, OF PAWTUCKET, RHODE ISLAND, ASSIGNOR OF ONE-HALF TO SUSAN A. BROWN, OF PAWTUCKET, RHODE ISLAND.

STOP-MOTION FOR LOOMS.

No. 886,150.

Specification of Letters Patent.

Patented April 28, 1908.

Application filed February 27, 1906. Serial No. 303,212.

To all whom it may concern:

Be it known that I, FELIX O'DONNELL, a citizen of the United States, residing at the city of Pawtucket, in the county of Providence and State of Rhode Island, have invented certain new and useful Improvements in Stop-Motions for Looms, of which the following is a specification, reference being had therein to the accompanying drawing.

10 This invention relates to stop motions for weft replenishing looms, and has for its object to produce a simple and effective stop motion that may be attached to the weft replenishing mechanism and one that may 15 be set so as to stop the loom automatically when the last cop has been discharged from the cop carrying wheel, or when said wheel arrives at any predetermined position in the course of a revolution.

20 This invention is an improvement on the mechanism for this purpose illustrated and described in my United States patent issued July 25, 1905, No. 795,364.

The invention is fully set forth in this 25 specification and more particularly pointed out in the appended claims.

In the accompanying drawings: Figure 1—is a side elevation of part of the loom and replenishing mechanism illustrating the stop mechanism attached to the cop carrying wheel. Fig. 2—is a skeleton view in perspective illustrating the actuating arm and the mechanism through which the stopping lever is released and thrown off when the 35 actuating arm is raised. Fig. 3—is a central longitudinal section showing the tripping device connected to the outer end of the shaft on which is mounted the cop carrying wheel. Fig. 4—is a sectional end view of the ratchet 40 on line 4—4 of Fig. 3, showing the spring actuated pawl engaging the teeth in the hub. Fig. 5—is an end view of the hub and its adjusting ring showing the indicating figures 45 the ring may be set to stop the loom at any predetermined position.

Referring to the drawings, at 1—1 are the end frames of the loom, and 2 is a portion of the loom arch which is supported from 50 said frames.

3 is the breast beam connecting the two end frames together.

At 4 is the frame work on which is mounted the weft replenishing mechanism. At 5 is 55 the shaft journaled at 6 in said frame to

which shaft is fixed the cop carrying wheel 7 on one side of the bearing, and the adjustable tripping stop mechanism on the opposite side of the said bearing. This tripping device is constructed of a flanged hub 9 60 keyed to the shaft 5, the periphery of this hub is cut with ratchet teeth 10, the number of these teeth corresponding with the number of cop holders 11 on the cop carrying wheel 7, and these teeth are lined off and numbered 65 on the face of the flange 14, see Fig. 5. Mounted on this hub is the adjustable ring 12 in which is held the spring actuated pawl 13 that engages the teeth of the hub. This pawl works in a hole 15 in the ring, and is 70 pressed downward by the spring 16 which spring is held in position by the screw plug 17. Near one edge of this ring is an annular groove 18 to receive and guide the actuating arm 19. This arm is pivoted at 20 to the 75 frame and extends forward over the collar and a short distance in front of the same. As a matter of convenience the arm is curved at 21 to conform somewhat to the circular groove 18 in the collar. Projecting 80 downward from the underside of this arm is the tooth 22 the edge of which rides on the bottom of the groove in the collar and serves to support the free end of the actuating arm 19. The engaging face of this tooth 22 is 85 beveled back at 23 (see Fig. 2) so that the tripping pin 24, that is set across the said groove for this purpose, may ride under the said beveled face of the tooth and raise said actuating arm in the course of the revolution of the collar. The free end of this actuating lever is connected to the rocker shaft 25 through the connecting rod 26 and lever 27 and when said actuating arm is raised the shaft 25 is rotated and the arm 30 is caused 90 to engage the knock-off lever 28 and actuate the same to throw the stop lever 29 out of engagement with its usual retaining notch, allowing the same to spring back and stop the loom. Often times it is found convenient and desirable to connect other stop 95 motions to this rocker shaft 25, which shaft is placed beneath the breast beam 3, it is therefore necessary that connections to said shaft should be so arranged that each stop motion connected thereto should work entirely independent of the other. To accomplish this I have provided an elongated hole 31 in the arm 27 through which the connection 26 passes, thereby allowing said 100

105 connection 26 to pass through the hole 31 in the arm 27.

arm to be raised freely when actuated by the rotating of said shaft from any other cause without affecting the position of the actuating lever 19 in question. This stopping device may be applied to any rotary cop carrying mechanism and is not confined to any particular type.

The operation of the mechanism is further described as follows: The rotary cop carrying wheel to which my device is attached is of the well-known type and it may be constructed and operated in any desired manner.

It has heretofore been found necessary for the operator of this class of looms to constantly watch the same when in operation so as to stop it when the last cop has been transferred from the carrier wheel to the shuttle in order to prevent the transferring mechanism from operating at each stroke of the loom, thus preventing racking or unnecessary wear and tear on the transferring mechanism. My device is of a very simple construction which may be connected in any convenient manner to the rotating cop carrying wheel. It may be connected to the wheel and set to stop the loom at any predetermined point, or at the transferring of any particular cop, it usually being set however, to stop the loom after the last cop has been transferred into the shuttle.

To simplify the setting of the tripping mechanism I have numbered each cop retained on the wheel, as shown in Fig. 1, and I have also numbered the ratchet teeth in the hub, the numbers appearing on the face of the hub at 14, as shown in Figs. 1 and 5. The number of said ratchet teeth must correspond exactly with the number of cop holders on the wheel. In order to set the device so that it will operate at the positioning of any given cop, the ring 12 that carries the spring pressed pawl 13 and also the tripping pin 24, is turned around by hand on the hub until the indicating mark opposite the said pin registers with the number of the cop carrier at which the loom is to be stopped. For instance, if it is desired to stop the loom after cop No. 10 has been transferred into the shuttle, the collar 12 is rotated on the hub until the said indicating mark registers with number 10 on the flange 14, the pawl 13 will then engage the necessary tooth in the hub and retain the ring in this set position to rotate with the cop carrying wheel. Then as

the said wheel turns step by step as one cop 55 after another is transferred therefrom into the shuttle, this tripping pin 24 finally reaches the position shown in Fig. 2, where it comes in contact with the inclined face of the tooth on the actuating arm 19, riding under the same and raising said arm which, through the mechanism described above, throws off the stopping lever and the loom is instantly and automatically stopped.

This mechanism is extremely simple and 65 practical in construction, easily attached to the loom and obviates the necessity of constant watchfulness on the part of the attendant thereby enabling him to operate more machines and effectually prevents unnecessary wear and tear of the weft replenishing mechanism.

Having thus described my invention, what I claim as new and desire to secure by Letters Patent, is:

1. In a device of the character described, a stop lever, rotary means for carrying cops to be transferred into a shuttle, actuating means rotated by said cop carrying means, means engaging said actuating means, and a 80 connection between said engaging means and said stop lever whereby the latter is knocked off to stop the loom at a predetermined point in the rotation of the cop carrier.

2: In a device of the character described, 85 rotary means for carrying cops to be transferred into a shuttle, actuating means rotated by said cop carrier, a lever engaging said actuating means, a rock shaft and a positive connection between said lever and said shaft 90 whereby the loom will be automatically stopped at a predetermined position of said carrier.

3. In a device of the character described, rotary means for carrying cops to be transferred into a shuttle, actuating means rotated by said cop carrying means, a lever engaging said actuating means, a rock shaft, a positive connection between the engaging end of said lever and said shaft whereby the 100 loom will be automatically stopped at a predetermined position of said carrier.

In testimony whereof I affix my signature in presence of two witnesses.

FELIX O'DONNELL.
